UNITED STATES PATENT OFFICE.

ALPHONSE R. PERRIN, OF WESTBROOK, MAINE, ASSIGNOR TO SACO-LOWELL SHOPS,
OF BOSTON, MASSACHUSETTS, A CORPORATION OF MASSACHUSETTS.

WARPING MACHINE FOR BEAM DYEING.

Original application filed December 23, 1922, Serial No. 508,755. Divided and this application filed April 7, 1924. Serial No. 704,548.

To all whom it may concern:

Be it known that I, ALPHONSE R. PERRIN, a citizen of the United States, residing at Westbrook, in the county of Cumberland 5 and State of Maine, have invented certain new and useful Improvements in Warping Machines for Beam Dyeing, of which the following is a specification.

My invention relates to beam dyeing and 10 means by which the warp beams may be wound more loosely and porously and so that the dye will penetrate a greater number of warp threads than under the old and well known process. The present invention 15 is a divisional application of No. 508,755, filed December 23, 1922.

The prime object of the present invention is to produce a soft warp by speeding up the yarn delivery to the beam so that the 20 yarn will keep a trifle ahead of the speed of the surface velocity of the beam whereby the yarn is fed in a slack condition to the beam. The penetrability of the dyes will thereby materially be increased.

According to the present process of beam dyeing, the warps or other yarns are wound upon a hollow perforated arbor or barrel and are placed bodily in a steam-tight retort. The dye is subjected to pressure in 30 the retort, connection being made with the inside of the hollow arbor or barrel and the outside of the same, so that the dyes are forced by the pressure through the body of the warp into the hollow arbor and also in 35 the reverse direction.

Thus, the dye is forced through the warp from the periphery of the beam inward toward the center and also in the opposite direction, passing back and forth until the 40 yarn is entirely dyed.

In carrying out this process in practice, it is found that there is a limit to the amount of yarn that can be placed on a beam as the permeability of the mass of 45 yarn decreases as the roll or beam grows larger and denser.

Thus, in dyeing cotton warps, it is found that about 8000 yards is the limit for a single beam as the dye will not penetrate through a greater thickness than this when wound in the ordinary way and with the usual tension on the warp beam.

In dyeing warp yarns, the yarn is wound

on the hollow metal arbor or barrel by means of a rotating cylinder. 55

The warp beam carrying its warp rests directly on the cylinder from which it takes its motion by frictional contact with the surface of the cylinder.

The size of the beam when the winding 60 process first begins is about 12 inches in diameter but as the yarn accumulates it builds up to a diameter of approximately 23 inches, when the beam is completely filled. The consequence is that as the beam fills up 65 the pressure on the driving cylinder becomes relatively very great and as a consequence the yarn is compressed becoming more and more dense and impermeable as 70 the size of the warp beam grows greater.

As a consequence, it is necessary to stop the accumulation on the warp beam long before it is entirely filled because it becomes impermeable to the dye by reason of the 75 dense character of the beam yarn as it builds up on the hollow arbor.

As a result of this condition, much time and expense are wasted in limiting the quantity of yarn treated in a single dyeing operation. 80

According to my invention, I render the yarn as it winds on the beam permeable to the dye by delivering the yarn to the beam at a speed slightly in excess of the surface speed of the beam as the yarn builds up on 85 the beam.

As a result of this operation, I build up what is called a "soft" beam by winding the yarn on the arbor with a uniform pressure which averages much less than its normal pressure, thus imparting to the beam as a whole a softness and permeability which allows the dye to pass freely through it. 90

In the form in which I prefer to carry out my invention, I suspend the shaft of the 95 warp beam on the arms of a pair of pivotal counter-weighted levers so that as the beam builds up with yarn it is forced by contact with the driving cylinder nearer to the fulcrum of the levers. Thus, the counter-weights by exerting continuously increasing leverage tending to lift the beam, are able to relieve the driving cylinder of an increasing portion of the weight of the beam and to cause the beam to exert on the cylinder 100 always a substantially uniform pressure,

this pressure being always less than the normal pressure.

The yarn beam as thus built up, becomes a uniform lightly wound permeable mass of yarn soft and yielding to the touch and in the best possible physical condition to be acted upon by the dye in the process of beam dyeing.

- By the use of my improved system of dyeing warp beams, I have nearly doubled the amount of yarn which may be placed on any given base, thus effecting a great saving in the time and expense of beam dyeing with other advantages hereinafter pointed out.
- 15 In the accompanying drawing, I show a warping device arranged to make soft and permeable warp beams in accordance with my invention.

In the drawing:—

- 20 Fig. 1, is an end elevation of the beam and adjacent parts,

Fig. 2, is a rear elevation of the same,

Fig. 3, is a section on an enlarged scale on the line 3—3 of Fig. 1,

- 25 Fig. 4, is a section on the line 4—4 of Fig. 2,

Fig. 5, is a section on the line 5—5 of Fig. 2.

- 30 Fig. 6, is an elevation of one end of the spiral spring comb for guiding the yarn just before it passes to the beam,

Fig. 7, is a section on the line 7—7 of Fig. 2,

- 35 Fig. 8, is a cross section on the line 8—8 of Fig. 5 and,

Fig. 9, is a cross section on the line 9—9 of Fig. 5.

Referring to the drawing, 1 is the perforated hollow metal barrel on which the 40 yarn is wound, 2 is the friction roll over which the yarn passes before reaching the beam, 3 is the guide roll placed next before the friction roll, 4 is the first comb located in front of the guide roll, 5 is the 45 driving cylinder which partially sustains the weight of the barrel and the yarn wound thereon and 6' is the head of the beam.

The beam 1 is provided with a central arbor 6 which is detachably mounted in pivoted arms 9. These arms 9 are supported by counter-balancing mechanism comprising weighted levers 16 fulcrumed intermediate of their ends and having curved arms 14 supporting the free ends of the pivoted 55 arms 9 on which the beam 1 is mounted. The arms 9 permit the necessary movement of the beam away from the driving cylinder 5 as the yarn builds up on the beam 1. As the yarn builds up on the beam 1, 60 it will increase in weight and at the same time, the beam will move upwardly away from the axis of the drive cylinder 5. This upward movement of the beam also carries its axis inwardly with respect to the fulcrum point of the weighted levers so that

the leverage and the counter-balancing effect of the weighted levers gradually increases with the increased weight of the beam. This operation will continue and the beam will travel slowly towards the fulcrum point of the weighted levers and the weighted arm of the levers will swing downwardly from the full line position shown in Fig. 1 of the drawings to the dotted line positions shown in the said figure. When the beam is at the limit of its upward movement, it is forced bodily forward, causing it to drop over the weighted levers onto a truck or other receptacle by which it is to be removed.

In order to produce the most loose and permeable beam it is desirable not only to relieve the pressure or tension between the beam and the driving cylinder as explained but it is also desirable to feed the yarn to the beam with as little tension as possible at the same time laying it smoothly and evenly on the beam.

The speed and friction of the friction roll 2 is such that the yarn delivered by it will have a speed slightly greater than the speed of the surface of the beam 1 and it will be obvious that the slackener the yarn is fed to the beam, the softer will be the beam and more readily the die will penetrate.

I interpose between the friction roll 2 and the beam a comb of special construction which has the quality of guiding a very slack yarn and laying it on the beam with considerable regularity. My comb instead of being made up of pins or teeth in the usual way, is constructed of a spiral spring 30 held in an elongated tube 31 having a central rod 32 passing through the spring. The end of the rod passes through a sliding head 33 and an elongated screw 34 journaled in said head.

The head 33 has a spiral groove on its outer surface in which fits the spiral spring 30, the head being thus securely fastened to the end of the spring so that the spring may be expanded or contracted endwise by the movement of the head. To prevent the rotation of the head 33, a stop 35 slides in a longitudinal slot 36 formed in the tube 31.

The spring may be stretched or allowed to contract by the action of the screw 34 and this is effected by an annular nut 37 rotated by a hand wheel 38 and having an internal screw thread engaging the screw thread 34. Thus, when the hand wheel 38 is turned in one direction the head 33 is pulled toward the end of the tube 30, stretching out the spring and when it is turned in the opposite direction, it pushes in the head 33 allowing the spring to contract.

Thus, by the stretching and contracting of the spiral spring 30 any number of turns of the spring may be evenly distributed within a given space across the face of the

beam and a quickly adjusted comb produced which requires far less manipulation than a comb of ordinary construction.

The effective portion of the comb has 5 about half the cylindrical body of the tube removed with the ends left substantially complete.

The yarn passes through the coil as shown in Fig. 7, extending down by the upper 10 edge of the tube, thence by the lower edge passing inside of the central rod 32. It is not necessary to insert the central rod until the threads are placed in position between the turns of the spring when the rod is 15 slipped in and the comb is complete.

The tubular comb and spring are preferably fixed at one end with the opposite end slideable within the tube as shown in Figs. 5 and 6.

20 It is to be understood that the counter-weighting mechanism as shown in Figs. 1 and 2 is duplicated at each end of the beam so that the counter-weights at each end act in concert to relieve the weight of the beam 25 on the cylinder 5.

By the use of a comb and particularly the improved comb, herein set forth, between the friction roll and the beam and by the reduction of the pressure between the 30 cylinder and the beam, I am enabled to relax the tension of the yarn as it is wound on the beam and still produce an even body of yarn and an even degree of permeability resulting in more even distribution of the 35 dye.

If the tension on the yarn is relaxed by increasing the speed of the friction roll, still retaining the high pressure of the old apparatus, the yarn as it builds up forms 40 ridges which the excessive pressure is apt to topple or crush over, forming streaks when the beam dyeing process is applied. By relieving the pressure between the beam and the cylinder, and relieving the tension 45 on the yarn by speeding up the friction roll and inserting a comb between the friction roll and the beam, I embody a combination of elements resulting in a soft beam of great permeability.

50 In addition to the advantage of treating a greater quantity of yarn on a single beam, I am enabled by the use of my invention to extend the adaptability of beam dyeing to a class of dyes which could not 55 before have been used on account of the fact that they would not be forced to penetrate the solid body of yarn produced by the old process and this is particularly true of the more delicate shades of color where even 60 permeability is most desirable.

While I have shown one form of mechanism for relieving the tension or pressure

on the beam, other means may be devised for winding the yarn on the beam so that it will become more permeable.

65

In the manufacture of the machines like the present one for making soft warps and where such machines have to be made applicable to different mills, running different numbers of yarn, my machine is arranged so that it may be applied differently to different sizes of yarn and therefore it is necessary to cover by patents combinations of the different elements which may be used according to circumstances.

70

75

It is obvious that in any device of this sort it is necessary to use the beam and the driving cylinder or its equivalent for driving the beam.

When fine yarn is used which naturally tends to pack solidly on the beam a dense impermeable body of yarn, it is necessary to gradually relieve the pressure on the beam as it builds up.

80

This is done by the counter-weighted levers shown, by which the beam is gradually drawn away from the driving cylinder.

85

In such cases, where fine yarn is used, it is necessary to combine with the beam even, 90 when gradually relieved of the pressure, the comb located between the friction roll and the beam.

90

The reason for this is that if the comb is not present to guide the yarn and one 95 strand of yarn happens to break, the machine tender has difficulty in finding the broken thread unless the thread can be found exactly where it belongs. The comb by guiding the yarn aids the operator to 100 find the broken end.

On the other hand, if coarse yarn is used it is not always necessary to use the counter-weighted lever for separating the beam from the driving cylinder nor is it necessary to make use of the comb for guiding the yarn onto the beam but it is necessary to regulate the speed by which the yarn is fed to the beam so that it will always remain slack.

105

I claim:—

In a warping machine for beam dyeing the combination of a warping beam, a driving cylinder for the same, a friction roll for delivering yarn to said beam at a speed slightly in excess of the surface speed of said beam, a comb interposed between said friction roll and said beam adjacent to said roll for immediately straightening the yarn as it comes from said friction roll, the said friction roll being separated from said beam by a space free and clear from parts which would interfere with the yarn.
